COMBINED CALENDAR AND MEMORANDUM PAD HOLDER

Michael M. Lucks, Brooklyn, N. Y.

Application February 21, 1958, Serial No. 49,754

Term of patent 14 years

(Cl. D74—1)

Fig. 1

Fig. 2

Fig. 3

Fig. 2 is a bottom perspective view thereof;

Fig. 3 is a bottom plan view; and

Fig. 4 is a top plan view thereof.

I claim:

The ornamental design for a combined calendar and memorandum pad holder, substantially as shown.
